UNITED STATES PATENT OFFICE.

WILLIAM S. GRANGER, OF PROVIDENCE, RHODE ISLAND, ASSIGNOR TO THE GRANGER FOUNDRY AND MACHINE COMPANY, OF SAME PLACE.

CLOTH-CALENDERING ROLL.

SPECIFICATION forming part of Letters Patent No. 407,858, dated July 30, 1889.

Application filed September 13, 1888. Serial No. 285,308. (No model.)

To all whom it may concern:

Be it known that I, WILLIAM S. GRANGER, a citizen of the United States, residing at Providence, in the county of Providence and State of Rhode Island, have invented new and useful Improvements in Cloth-Calendering Rolls, of which the following is a specification.

This invention relates to calendering-rolls, and particularly to that class thereof to be used for calendering and finishing muslin, print-cloths, and similar textile fabrics, the object being to provide an improved roll for said use; and the invention consists in the peculiar construction of the roll, all as hereinafter fully described, and pointed out in the claim.

In the drawings forming part of this specification, Figure 1 is a side elevation of a portion of a calendering-roll constructed according to my invention, a portion of the body of the roll shown in this figure being shown in longitudinal section to illustrate as far as may be the materials of which the roll is composed. Fig. 2 is a perspective view of a portion of the roll, one end thereof being shown broken off.

In the drawings, 4 indicates the ordinary shaft of a calendering-roll, and 3 the roll itself, which is in practice built up on the shaft 4, as below described, said shaft being ordinarily provided with a fixed collar 6 near its journal at each end. A metallic roll-head 5 is locked against the end of the roll 3 in any suitable manner, one means of locking said roll being shown in the drawings, consisting of two segments 7 of a split ring, which are inserted in an annular groove in shaft 4 between the outer face of said head 5 and the collar 6 on the shaft in the positions shown in Figs. 1 and 2, whereby said head is rigidly locked against each end of the roll 3, and thereby such connection is made between the latter and the shaft 4 as causes the shaft and the roll to rotate in use as one.

The essential feature of novelty in the calendering-roll which constitutes the subject-matter of this invention consists in the combination of materials from which the roll 3 is made, said materials consisting of corn-husks and cotton mixed or commingled in a common

mass by passing about equal portions of each substance through a coarse lapper or carding-machine, whereby the husk material is more or less broken up and suitably intermingled with the cotton.

In Fig. 1 the said materials are as far as practicable illustrated in the sectional portion of the roll there shown, and in that figure *a* indicates the cotton, and *c* portions of the husk matter.

The manner of constructing the roll from said materials is that ordinarily pursued in making rolls from other similar ones—that is to say, the shaft 4 is placed in an upright position with one of the heads 5 thereon near its lower end in or on a suitable base under a hydraulic press. The mixed cotton and corn-husks above described are then applied and arranged in proper position around the shaft, and the said hydraulic press is brought to act to compress and solidify said material, forcing it downward against the said head near its lower end, and little by little more and more material is added to the roll and compressed as before, until the roll shall have attained the desired length, when a second head is placed on the upper end of the roll and forced against the latter by said press, and is then locked in position, as described. The roll is then placed in a suitable lathe and is turned and finished ready for use.

The calendering-roll made as above described, and consisting of the said combination of materials, possesses certain advantageous characteristics not possessed by rolls heretofore made, said characteristics being those particularly adapted to the finishing of textile material of the classes above referred to, in that the cotton portion of the roll provides the requisite finishing and surface-polishing material and the husk portion of the material of the roll provides an elastic feature not possessed by the cotton alone, and the husk portion of the roll causes the latter to so act upon the fabric against which it rolls that the threads thereof are not injuriously flattened, for the reason that the face of the roll permits of certain temporary indentations therein which may be caused by the fabric, but which indentations, owing to the elastic action of the husk material, are of

only temporary duration, and hence such indentations or marks as may be impressed on the face of the roll in use cause no permanent injury thereto.

5 I am aware that it is common to make calendering-rolls entirely from cotton and entirely from corn-husks, and I do not claim rolls so made as my invention; but

What I claim as my invention is—

A calendering-roll for finishing cloth, consisting of commingled corn-husks and cotton, substantially as set forth.

WILLIAM S. GRANGER.
